UNITED STATES PATENT OFFICE.

HENRY DOERING, CHARLES DOERING, JR., AND MAX DOERING, OF CHICAGO, ILLINOIS.

DESIGN FOR A WATER OR LIQUID COOLER.

47,454.

Specification for Design.

Patented June 15, 1915.

Application filed April 5, 1915. Serial No. 19,383. Term of patent 7 years.

To all whom it may concern:

Be it known that we, HENRY DOERING, CHARLES DOERING, Jr., and MAX DOERING, citizens of the United States, residing at Chicago, in the county of Cook and State of Illinois, have invented a new, original, and ornamental Design for Water or Liquid Coolers, of which the following is a specification, reference being had to the accompanying drawing, forming a part thereof.

In the drawing:—Figure 1 illustrates our new design of water or liquid cooler in ele-

vation, showing the front side thereof. Fig. 2 is a similar view showing the rear side thereof.

We claim:—

The ornamental design for a water or liquid cooler as shown.

HENRY DOERING.

CHARLES DOERING, JR.

MAX DOERING.
